UNITED STATES PATENT OFFICE.

HANS ABRAHAM ISBERG, OF LONG ISLAND CITY, ASSIGNOR TO CHARLES FRED. HODSDON, OF NEW YORK, N. Y.

PORTABLE WOODEN BOOTH.

SPECIFICATION forming part of Letters Patent No. 442,979, dated December 16, 1890.

Application filed July 10, 1890. Serial No. 358,237. (No model.)

To all whom it may concern.

Be it known that I, HANS ABRAHAM ISBERG, a citizen of the United States, residing at Long Island City, in the county of Queens 5 and State of New York, have invented a new and useful Improvement in Portable Wooden Booths; and the following is declared to be a full, clear, and exact description of the same.

The object of my invention is to provide 10 voting-booths for use at polling-places during elections, as such booths are required by law in some States.

My invention consists in a booth that is made in connected sections that are readily 15 folded together, and the same are securely held in a distended condition by a locking-shelf, and the booth is provided with a door the lower edge of which is about two feet above the floor, so that the lower part of the 20 legs of the occupant can be seen.

My improved booth can be readily set up for use or knocked down with the connected 25 sections folded together, in which condition the booth occupies but a small space when packed for transportation or storage.

In the drawings, Figure 1 is an elevation, and Fig. 2 a vertical section, of my improved 30 booth at the line $z z$ of Fig. 3. Fig. 3 is a sectional plan of the same at the line $x x$, and Fig. 4 is a sectional plan at the line $y y$. Fig. 5 is a plan view of the booth folded.

The sections $a b c$, composing three sides of 35 the booth, are preferably about three feet wide and six feet long, and are each made of tongued and grooved boards vertically placed, and there are horizontal strips or frame-pieces $d d'$ at the opposite ends securing the boards and central horizontal strips or frame-pieces e upon the sections a and c , and a central 40 horizontal strip or frame-piece e' upon the section b . The section b is made, as a whole, with the horizontal top and bottom strips or frame-pieces $d d'$ and horizontal central strip e' , and I provide vertical strips or corner- 45 posts $f f'$, to which the strips d , d' , and e' are mortised to form a frame for the vertical tongued and grooved boards.

The front is made as a frame, having top 50 and bottom strips $d d'$ and vertical corner- 50 posts $g g$ connected together, and in the upper part of this frame a short-length door h

is hinged at one side to one post g , and said door fits into the rabbeted edges of said corner-posts, and a lock or catch of any desired form may be placed upon the door to secure 55 the same when shut; or spring-hinges may be employed. The lower edge of the door is about two feet above the floor, so that beneath it the legs of the occupant of the booth may be seen. 60

The sections a and c , which are opposite each other, are made alike of two narrow vertical frames with top and bottom strips $d d'$ and central strips e , which are connected to vertical strips or posts $i i'$, $k k'$, $l l'$, and $m m'$ with the outer faces of the tongued and grooved boards. I connect these sections together, so that they fold into a compact flat form, the half-sections of a and c folding inwardly between the section b and the front, 70 and in this condition the folded booth can be transported or stored away.

The vertical posts $f f'$ of the section b are connected to the posts i and l of the folding sections a and c by inside hinges 45, and the 75 vertical posts $g g$ of the front are connected to the posts k and m of the folding sections a and c also by inside hinges 67.

The folding sections of a and c are connected by hinges 8 and 9 upon the outside. 8c These hinges I prefer to place on line with the horizontal strips. The parts fold in the direction of the dotted arrows.

The vertical meeting faces of the corner-posts $f f$, $i i'$, $k k'$, $g g$, $m m'$, and $l l'$ are 85 tongued and grooved, preferably, along the under edges, so that when the sections are opened to form the booth there are no open joints or cracks through which the occupant of the booth can be seen from the outside. 90

The upper edges of the strips $e e$ of the side sections adjacent to the section b are preferably notched, and I provide a shelf n with notched ends, and said shelf fits into the notches of the strips $e e$. I prefer to make 95 these notches as deep as the thickness of the shelf n , so that when the shelf is in place its surface will correspond with the top edges of the strips $e e$, and I prefer to make the strip e' of the section b of the same width as the 100 strips $e e$, so that its top edge may correspond with the surface of the shelf, as thereby there

will be no space at the back of the shelf; or the top edge of the strip may be above the shelf, if desired. When the shelf is in place, its weight is carried upon the strips *e e*, and 5 the notched ends of the shelf bear against the faces of the said strips and serve to keep the sections composing the booth distended after being opened out. The shelf also provides a place for the voter to arrange his ticket 10 upon.

These booths are designed for use at polling-places in times of elections as a place where each voter can examine, mark, and arrange his ticket in secrecy, as provided by law in 15 some States, the shelf *n* being a convenient and necessary addition to the booth for the uses herein set forth.

It will be noticed that it is but the work of a few minutes to set up or take down these 20 booths, and that there are no parts that can become lost or misplaced, as the shelf is the only detachable piece going to make up the booth, and said shelf can be laid within the folded booth against the back *b* between the 25 strips *e'* and *d'*.

These booths are opened at the top and bottom, and the same are to be about six feet high, as required by law, and at this height no man of ordinary stature can look over the 30 top. The frames of the sections *a*, *b*, and *c*, instead of being surfaced with tongued and grooved boards, may be surfaced with canvas or other similar fabric, in which case the voting-booth is made lighter in weight and 35 equally efficient.

I claim as my invention—

1. The combination, with the frame forming the front and the short-length door, of the section *b*, the two-part sections *a* and *c*, hinges 40 connecting the parts, and a shelf or brace for

holding and locking the parts when distended, substantially as set forth.

2. The combination, with the frame forming the front and the short-length door, of the section *b*, composed of a frame, tongued and grooved boarded surface, the sections *a* and *c*, each composed of two narrow frames, and tongued and grooved boarded surfaces, hinges upon the inner corners connecting the two-part sections *a* and *c* with the section *b* and 45 with the front frame *g*, and hinges upon the outside connecting the two parts of the sections *a* and *c*, whereby the sections *a* and *c* fold in between the front and section *b*, substantially as set forth. 50

3. The combination, with the front frame and short-length door hinged thereto, of the section *b*, the two-part sections *a* and *c*, having central strips *e e*, notched upon their upper edges adjacent to the section *b*, the shelf *n*, notched at its end corners and adapted to set upon and against the strips *e e*, and hinges connecting the various sections and front together, substantially as set forth. 55

4. The combination, in a portable folding booth, of a front section having a frame and door, a back section and side sections, each having a frame and covering, hinges for uniting all the sections together at their meeting edges, so that the sections will fold without 60 being disconnected at any place, and a movable shelf, serving also to keep the sections in position when in use, substantially as specified. 7c

Signed by me this 30th day of June, A. D. 1890.

H. A. ISBERG.
